UNITED STATES PATENT OFFICE.

HERBERT V. SHEPPARD, OF WORCESTER, MASSACHUSETTS.

ADVERTISING DEVICE.

1,240,379.

Specification of Letters Patent. Patented Sept. 18, 1917.

Application filed March 31, 1916. Serial No. 88,140.

To all whom it may concern:

Be it known that I, HERBERT V. SHEPPARD, a citizen of the United States, residing at Worcester, in the county of Worcester and 5 Commonwealth of Massachusetts, have invented a new and useful Improvement in Advertising Devices, of which the following, together with the accompanying drawings, is a specification.

10 My present invention relates to an advertising device, comprising an illuminated screen upon which shadows are thrown by means of an opaque figure, and it has for its object to produce the appearance of movement of the opaque figure while the latter remains stationary. I accomplish this result by the operation of an apparatus as 15 hereinafter described, the novel features of my invention being pointed out in the appended claims.

Referring to the accompanying drawings, Figure 1 represents a front view of an advertising device embodying my present invention.

20 Fig. 2 is a plan view of the same, with the top or cover of the apparatus removed to disclose the interior mechanism.

Fig. 3 is a front view upon a larger scale, with the screen removed, and

25 Fig. 4 is a vertical sectional view on the plane of the broken line 4—4, Fig. 3.

Similar reference characters refer to similar parts in the different figures.

30 My improved advertising device comprises a box or casing 1 containing the operating mechanism. The front side of the casing is left open and is closed by a screen 2, of cloth or similar semi-transparent material. At some distance behind the screen 2 is mounted a stationary opaque figure 3, and at the rear of the figure 3 and at opposite corners of the box I place two electric lamps 4, 5. If the lamps 4 and 5 are lighted and extinguished alternately, the shadow of 35 the figure 3 will be thrown upon the screen 2 in different positions. When the lamp 4 is lighted, the shadow of the figure 3 will be thrown upon the screen between the points 6 and 7, and when the lamp 5 is lighted, the shadow of the figure 3 will be thrown upon the screen between the points 8 and 9. By thus shifting the position of the 40 shadows, the figure producing them will have the appearance of moving. The amount of apparent movement will depend

upon the distance between the screen 2 and the opaque figure 3.

The electric current for supplying the lamps 4 and 5 I utilize for operating the mechanism by which the lamps are alternately lighted and extinguished, which consists, in the present instance, of an electromagnet 10, comprising a core 11 around which a wire for conducting electricity is wound in multiple layers. At one end of 45 the magnet 10 is suspended an armature 12, capable of swinging freely upon a spindle 13 held in posts 14, 14. Bearing against the upper end of the swinging armature 12 is an insulated spring 15, which holds the 50 lower end of the armature 12 against a metallic contact piece 16.

At the opposite end of the magnet is suspended a second armature 17, capable of swinging freely upon a spindle 18 supported in posts 19, 19. The armature 17 carries at its lower end pins 20 and 21 projecting from opposite sides of the armature 17. Upon one side of the pin 21 is a blade spring 22, and upon the opposite side of the pin 20 55 is a blade spring 23. As the armature 17 hangs by gravity in a vertical plane, the pins 20 and 21 are out of contact with the springs 22 and 23. Wires 24 and 25 connect the spindles 13 and 18 with a source of 60 electricity, and the metallic contact piece 16 is connected by a wire 26 with one end of the wire coiled about the core 11 of the magnet. The opposite end of the coiled wire is connected with a wire 27 which is 65 connected with a wire 28 returning to the source of electrical supply, and thereby completing a circuit through the coils of the magnet. As the magnet becomes energized, the swinging armature 12 is drawn away 70 from the contact piece 16, which breaks the circuit and demagnetizes the core 11. When this occurs, the spring 15 will instantly throw the swinging armature 12 against the contact piece 16, again completing the circuit and energizing the magnet. The magnet 10 will, therefore, be rapidly brought 75 into and out of the electric circuit, the core 11 becoming magnetized and demagnetized in succession. When the core 11 is magnetized, the swinging armature 17 is drawn toward the magnet, bringing the pin 20 80 against the spring 23 and causing the current to pass through the wire 25, spindle 18, armature 17, spring 23 and wire 29 to the 85

lamp 5, the circuit through the lamp being completed by the wire 30 and wire 28.

As soon as the magnet becomes demagnetized, the spring 23, which has been 5 slightly compressed by the pressure of the pin 20, immediately throws the lower end of the armature 17 away from the magnet, the momentum of the armature carrying the pin 21 against the spring 22. The spring 22 is 10 connected by the wire 31 with the lamp 4, the circuit through the lamp 4 being completed by the wire 32 and wire 28. By the operation of the above described apparatus, the lamps 4 and 5 will be alternately lighted 15 and extinguished, causing the shadow of the opaque figure 3 to be shifted on the screen 2.

I do not wish to confine myself to the above described apparatus for alternately lighting and extinguishing the lamps 4 and 5 20 as I am aware that other means may be employed. The apparatus I have described, however, is simple and continuous in its operation so long as the source of electric current is supplied, and a single source of 25 electricity serves to illuminate the lamps and also to produce their alternation. The figure 3 may be of any fanciful design of a character adapted to produce the similitude of the moving object. In the accompanying 30 drawings the outlines of the figure are represented upon the screen in Fig. 1 in positions 33 and 34.

I claim:

1. An advertising device comprising a 35 screen, separated sources of illumination, an object placed between said sources of illumination and said screen but spaced from said screen, whereby a shadow will be thrown upon said screen by each source 40 of illumination but in different positions.
2. An advertising device comprising a semitransparent screen, an opaque figure placed behind said screen and spaced therefrom, two separate sources for illuminating

said screen placed behind said opaque object, and means for illuminating said screen from each of said sources alternately, whereby shadows of said object will be thrown upon said screen in different positions. 45

3. An advertising device comprising a semitransparent screen, an electric circuit, two separated electric lamps for illuminating said screen and forming part of said electric circuit, an opaque figure placed behind said screen and spaced therefrom, and in a position substantially midway between said electric lamps, and means for alternately breaking the electric circuit leading to each of said lamps, whereby the shadow 50 of said opaque figure will be thrown upon the screen in two different positions alternately. 55

4. An advertising device, comprising a screen, a figure spaced from said screen, 60 means for projecting a shadow of the figure on said screen, and means for changing the direction of the illumination, whereby the position of the shadow is changed. 65

5. The combination of a closed casing 70 having at one of its sides a semitransparent screen for the projection of a shadow thereon, an object at the rear of said screen, but spaced therefrom, capable of intercepting rays of light, two sources of illumination 75 closed in said casing in a plane at the rear of said object but spaced apart, whereby a shadow projected by each of said sources of illumination will be varied in position on said screen, and means for cutting off 80 the illumination of said screen from each of said sources alternately in rapid succession. 85

HERBERT V. SHEPPARD.
